Primary Examiner — Cathron Brooks*Assistant Examiner* — Andrew Nemeth(74) *Attorney, Agent, or Firm* — Bookoff McAndrews, PLLC**CLAIM**

The ornamental design for a display screen with graphical user interface, as shown and described.

DESCRIPTION

The FIGURE depicts a display apparatus including a graphical user interface.

The outermost broken line and the broken line circle illustrate an electronic device and form no part of the claimed design. The remaining broken lines are provided for the purpose of illustrating portions of the graphical user interface and form no part of the claimed design.
